Primary Examiner — John R Yeh*(74) Attorney, Agent, or Firm* — Adan Ayala(57) **CLAIM**

The ornamental design for a pressure washer, as shown and described.

DESCRIPTION

FIG. 1 is a front perspective view for a pressure washer according to the invention;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken lines in the drawings depict portions of the pressure washer that form no part of the claimed design.
